UNITED STATES PATENT OFFICE.

TELBERT L. RICHARDSON, OF BROCK, NEBRASKA.

SCREEN, CURTAIN, OR LIKE ARTICLE.

1,309,488.

Specification of Letters Patent. Patented July 8, 1919.

Application filed October 22, 1918. Serial No. 959,273.

To all whom it may concern:

Be it known that I, TELBERT L. RICHARDSON, a citizen of the United States, and a resident of Brock, in the county of Nemaha and State of Nebraska, have invented a new and Improved Screen, Curtain, or like Article, of which the following is a description.

My invention while more particularly designed for use in connection with a curtain or screen is adapted for use in any structure having a window or opening adapted to be closed, shaded, or screened by sheet material. For the purpose of illustration, I have shown my invention in connection with a window screen. The invention particularly relates to a screen, curtain or the like adapted to be wound on a spring roller or unwound therefrom.

20 The general object of the invention is to provide a novel means for maintaining the screen, curtain, or the like in flat form.

Other objects of the invention and its advantages will appear as the description proceeds.

Reference is to be had to the accompanying drawings forming a part of this specification, it being understood that the drawings are merely illustrative of one example 30 of the invention.

Figure 1 is a front elevation of a window frame and screen having my invention embodied therein;

Fig. 2 is an enlarged vertical section 35 through the upper portion of the structure as indicated by the line 2-2, Fig. 1;

Fig. 3 is an enlarged cross section as indicated by the lines 3-3 in Figs. 1 and 6;

Fig. 4 is a detail in vertical section on an 40 enlarged scale, the view being taken on the line 4-4, Fig. 1;

Fig. 5 is a transverse vertical section on the line 5-5, Fig. 6;

Fig. 6 is a vertical section at right angles 45 to Fig. 5;

Fig. 7 is a detail in transverse vertical section given to show locking means associated with the lower roller shaft of the actuating chain of the curtain for the screen or the like.

Fig. 8 is a fragmentary horizontal section taken through the lower bar attached to the screen.

The frame in connection with which my 55 improved screen, curtain, or the like is to be employed, is shown in the form of a metal

window frame 10 having stiles 11. A screen 12 or other suitable sheet material is secured at its upper end to a spring roller 13 mounted to turn in bearings 14^a within a housing 14 forming part of the frame 10.

The sheet material 12 extends from the roller 13 downwardly through a slot 15 in the bottom of the top rail 16 of the frame and said sheet at the side edges extends 65 through vertical slots 17 in the inner walls 11^a of the stiles 11. Along the side edges of the sheet material 12 within the hollow stiles 11, said sheet has applied thereto flexible strips 18 of metal or equivalent material, 70 and said strips are formed each with a vertical series of holes 19 to receive correspondingly spaced pins 20 extending from the outer side of a chain 21, here shown as an endless chain running over upper and lower 75 rollers 22 on shafts 23 turning in bearings in brackets 29, 30. The chain is made of flat links and the hinges are at the inside and adapted to engage in notches 25 in the rollers 22. The links of the chain 21 and hinges 80 thereof at one side edge of the chain runs adjacent to the inner walls 11^a and at the opposite sides the links and the strips 18 are overlapped by a guard plate 27 having a flange 28, whereby the strips 18 are prevented from being laterally disengaged from the chain pins 20 and said strips and the links are prevented from working outwardly 85 through the slots 17. A flap or packing strip 15^a may be provided at the slot 15 to 90 exclude flies and other insects.

To the lower edge of the sheet 12, a strip or bar 32 is secured and formed in sections adapted to clamp the sheet therebetween. The rear section 32^a of the strip has its front 95 wall extended at the ends forming projecting flanges 32^b which have holes 32^c to receive pins 20 of the chains 21. The front section 32 has a downwardly extending flange 32^d to overlap the sill 33 of the window frame 10 or like structure, and the arrangement is such that the said flange 32^d will overlap and form a closure at the bottom of the screen, or the like, between the same and the window, even though the 105 screen is not brought to its extreme lowermost position.

The spring roller 13 tends to wind up the sheet 12 and in order to hold the sheet material from being raised, locking means for 110 the lower shaft 23 is provided in the form of a ratchet wheel 34 and a gravity pawl 35

pivoted at one end as at 36 within a stile 11 and having its free end 37 extending through a slot 38 in the stile to the exterior thereof. Thus, by lifting the pawl 37 from 5 the ratchet 34, the spring roller 23 is free to roll the sheet material 12. The sheet material may be lowered by taking hold of the bottom bar 32. In the raising and lowering of the sheet material, the engagement of the 10 pins 20 with the strips 18 causes the chain to turn, so that the pins may release themselves from the strips 18 as the pins pass about the upper roller 22. The bar 32 will always be engaged with its pins 20 to maintain the connection 15 between the chain and the screen or the like on which the bar 22 is attached. Thus, the strips 18 will be maintained substantially flat against the adjacent face of the chain, the engagement of the pins and 20 the contact with the chain preventing any buckling of the sheet material. At the same time, the screen or the like may be readily raised or lowered and will be firmly held in the adjusted position by the pawl 35 and 25 ratchet 34.

I would state in conclusion that while the illustrated example constitutes a practical embodiment of my invention, I do not limit myself strictly to the mechanical details 30 herein illustrated, since manifestly the same can be considerably varied without departure from the spirit of the invention as defined in the appended claims.

Having thus described my invention, I 35 claim as new, and desire to secure by Letters Patent:

1. A frame presenting stiles, a roller mounted at the upper portion of said frame,

sheet material connected with said roller, means at the side edges of said sheet material presenting holes, chains in said stiles, pins on said chains adapted to engage in said holes, wheels over which said chains run, and means to hold the chains and sheet material from movement. 40

2. A frame presenting stiles, a spring roller mounted at the upper portion in said frame, sheet material secured to said roller to wind thereon or to unwind, said stiles having vertical slots through which the 45 sheet material extends, upper and lower wheels in said stiles, an endless chain extending about said wheels, pins on the chain, strips on the side edges of the sheet material and presenting holes adapted to receive said 50 pins, a ratchet turning with the lower wheel, and a pawl engaging said ratchet and extending to the exterior of the frame, whereby to release the ratchet and permit the spring roller to raise the sheet material. 55

3. A frame presenting stiles, a spring roller mounted at the upper portion of said frame, sheet material secured to said roller to wind thereon or to unwind, a bar carried by said sheet material at its lower edge, said bar presenting a depending flange adapted to overlap the frame at the bottom when the sheet material is lowered, end flanges on said bar extending into the said stiles, endless chains in said stiles, pins on the chains engaging the last mentioned flanges, wheels over which said chains run, and means associated with the lower wheel to prevent turning of the latter or to release the wheel. 60 65 70

TELBERT L. RICHARDSON.
